(57) **CLAIM**

I claim the ornamental design for a hip-pack with insulated receptacle, as shown and described.

DESCRIPTION

FIG. 1 is a front perspective view of a hip pack with insulated receptacle shown in use;

FIG. 2 is another perspective view thereof;

FIG. 3 is another perspective view thereof;

FIG. 4 is a front elevation view thereof;

FIG. 5 is a rear elevation view thereof;

FIG. 6 is a side perspective view thereof;

FIG. 7 is a top perspective view thereof; and,

FIG. 8 is a bottom perspective view thereof.

FIGS. 1-3 are reduced in scale and show the hip-pack being worn in an environmental setting. FIGS. 4-8 are same scale perspective views. The dashed lines in FIGS. 1-3, depicting a human form, a belt and a belt buckle form no part of the claimed design. The dashed lines on the article itself represent stitching and are part of the design.
